UNITED STATES PATENT OFFICE.

HERBERT S. HUMPHREY, OF KALAMAZOO, MICHIGAN.

DESIGN FOR A CASING FOR WATER-HEATERS.

50,839.

Specification for Design.

Patented May 29, 1917.

Application filed April 9, 1917. Serial No. 160,903. Term of patent 14 years.

To all whom it may concern:

Be it known that I, HERBERT S. HUMPHREY, a citizen of the United States, residing at Kalamazoo, in the county of Kalamazoo, State of Michigan, have invented a new, original, and ornamental Design for a Casing for Water-Heaters, of which the following is a specification, reference being had to the accompanying drawing, forming a part thereof, in which—

Figure I is a front elevation, and Fig. II a side elevation showing my new design.

I claim:

The ornamental design for a casing for water heaters, as shown.

HERBERT S. HUMPHREY.

Witnesses:

EVA FRANCK,
F. A. LEMKE.
